UNITED STATES PATENT OFFICE.

GEORGE C. HESTER, OF CHICAGO, ILLINOIS.

DESIGN FOR A SASH-RAIL FOR STORE-FRONT CONSTRUCTION.

49,144.

Specification for Design.

Patented June 6, 1916.

Application filed January 17, 1916. Serial No. 72,637. Term of patent 14 years.

To all whom it may concern:

Be it known that I, GEORGE C. HESTER, a citizen of the United States, residing at Chicago, in the county of Cook and State of Illinois, have invented a new, original, and ornamental Design for Sash-Rails for Store-Front Construction, of which the following is a specification, reference being had to the accompanying drawing, forming part thereof.

In the drawing the figure is a perspective view of a sash rail showing my new design.

I claim:

The ornamental design for a sash rail for store front construction as shown.

GEORGE C. HESTER.
